HAND CARRIED PAPER POMPON

Harold E. Barry, Oakland, Calif.

Application September 25, 1950, Serial No. 12,351

Term of patent 14 years

(Cl. D59—2)

To all whom it may concern:

Be it known that I, Harold E. Barry, a citizen of the United States, residing at Oakland, State of California, have invented a new, original, and ornamental Design for a Hand Carried Paper Pompon, of which the following is a specification, reference being had to the accompanying drawings, forming a part hereof, wherein:

Fig. 1 is a perspective view of a hand carried paper pompon, showing my new design;

Fig. 2 is a top plan view thereof; and

Fig. 3 is an elevational view thereof as it appears in inverted position.

I claim:

The ornamental design for a hand carried paper pompon, substantially as shown.

HAROLD E. BARRY.
